THREADED
THREAD HOLDER DRIVEN FROM TAKE-UP ROLL

Filed April 29, 1944

UNITED STATES PATENT OFFICE

2,365,667

THREAD HOLDER DRIVEN FROM TAKE-UP ROLL

Walter H. Wakefield, Worcester, Mass., assignor to
 Crompton & Knowles Loom Works, Worcester,
 Mass., a corporation of Massachusetts

Application April 29, 1944, Serial No. 533,365

11 Claims. (Cl. 139—247)

This invention relates to improvements in thread holder mechanisms for weft replenishing looms and it is the general object of the invention to provide means by which a roughened or friction cloth engaging surface of the take-up roll can be utilized to rotate the thread gears of a thread holder.

In weft replenishing looms more particularly of the multicolor type the reserve bobbins are arranged in the vertical stacks of a magazine and have weft ends extending to a thread holder. As the bobbins descend in the stacks slackness develops in their weft ends and it is desirable to take up this slackness to prevent the weft ends from being broken by the lay. A form of thread holder for this purpose which has gone into general use employs a pair of weft end engaging gears which mesh with each other and turn in such directions as to draw the weft ends away from the bobbin magazine and keep them taut. The thread gears should preferably rotate at a slow rate and continuously throughout loom operation not only for the purpose of taking up the aforesaid slackness, but also to take up any slackness in the weft ends which results from rotation of the bobbins on their axes in the magazine caused by loom vibration.

The take-up roll of a loom generally operates at a slow rate which is more or less proportional to the rate at which replenishing operations occur due to the relationship between the size of the weft, the number of picks per inch in the fabric advanced by the take-up roll, and the fact that coarse yarn requires replenishment more frequently than does fine yarn. It is an important object of my present invention to provide driving connections between the thread gears of the thread holder and the take-up roll, the driving connections preferably including a small roll held against the friction surface of the take-up roll and caused by the latter to turn for the purpose of operating the driving connections.

The take-up roll is ordinarily mounted to rotate in bearings projecting forwardly from the front of the loom, and when the take-up roll is in high position its bearings are mounted on the breast beam. It is a further object of my present invention to mount the aforesaid small roll on the take-up roll bearing adjacent to the magazine in such manner that it will be held against the take-up roll by resilient means which is yieldable to compensate for any irregularities in the surface of the take-up roll.

After fresh bobbins have been placed in the magazine it is customary for the operator to lay the new weft ends over the thread gears and then spin or turn the latter manually to tighten the ends and draw them between the gears. When positive driving connections exist between the thread gears and the small roll it is desirable

that the latter be able temporarily to move out of driving relation with the take-up roll to permit manual turning of the gears. It is another object of my invention to provide a resilient or yielding mounting for the aforesaid small roll so that the latter can move out of driving engagement with the take-up roll when acted upon by a rotary force transmitted through the driving connections from the thread gears when the latter are turned manually.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a diagrammatic plan view of a loom having my invention applied thereto,

Fig. 2 is an enlarged vertical section on line

2—2 of Fig. 1,

Fig. 3 is a plan view of the structure shown in Fig. 2,

Fig. 4 is a vertical section on line 4—4 of Fig. 3, and

Fig. 5 is an enlarged vertical section on line 5—5, Fig. 1.

Referring particularly to Fig. 1, I have shown a weft replenishing loom frame 10 having a breast beam 11 and a lay 12 which reciprocates under a magazine M which holds reserve bobbins B, four stacks of bobbins being indicated in Fig. 1. From these reserve bobbins extend weft ends W to a thread holder mechanism designated generally at H.

The loom includes in its construction cloth take-up means comprising a roll or cylinder 15 over which extends the fabric F being woven. The take-up roll in the present instance is in high position and is supported on bearings extending forwardly from the breast beam. In Figs. 1, 2 and 3 one of these bearings is shown at 16 with its bearing cap 17 to receive the gudgeon 18 of the take-up roll. The latter is turned in the direction of arrow a, Fig. 2, during loom operation by well-known mechanism not shown.

The thread holder H has front and back meshing thread engaging gears or geared members 19 and 20, respectively, which may be mounted on the holder as shown, for instance, in patent to

Payne No. 1,842,731. It is thought sufficient for the present purposes to state that the gears 19 and 20 are caused to rotate in such a direction as to tension the weft ends W which pass downwardly between them, and that these gears mesh with each other so that the driving of one of them causes rotation of both.

The matter thus far described may be constructed and operated in the usual manner.

In carrying my present invention into effect I provide a train of driving connections or mech-

anism which transmits a rotary force from the friction or roughened cloth engaging surface 21 of the take-up roll 15 to the forward gear 19 of the thread holder H. The surface 21 may be made of sandpaper, burred sheet metal, or the like, and rotates about the axis of the take-up roll as the latter turns during loom operation to advance the cloth as it is woven. A stud 25 is screw threaded at 26 into bearing 16 and is held in position by check nut 27. The stud 25 is substantially parallel to the take-up roll and is located below and to the rear of the latter as indicated in Fig. 2.

The stud extends beyond the adjacent end of the take-up roll and has mounted thereon a lever 28 the lower end of which is provided with a hub 29 rotatable on the stud. The lever extends upwardly and has a bearing 30 in which rotates a stub shaft 31. That end of shaft 31 remote from the bearing 16 has secured thereto rotary means, such as a small friction roll 32, which is made of any suitable material having preferably a rough or deformable surface for the purpose of establishing frictional driving conditions with the take-up roll surface 21 so that the latter will cause rotation of the small roll. Thus, the small roll 32 may be covered with felt, rubber, leather, sand, or like material, which will cooperate with the take-up roll surface 21 to effect turning of roll 32.

That end of stub shaft 31 adjacent to the bearing 16 projects beyond bearing 30 and has tapered screw threads 33 which receive a similarly tapped nut 34. The tapered end of the stub shaft is split as at 35 so that tightening of nut 34 will clamp the split parts of the end of the stub shaft against the core 36 of a flexible shaft designated generally at 37 and including in its construction a sheath 38. The core 36 is thus caused to rotate whenever shaft 31 turns in the bearing 30.

In order to insure engagement of the roll 32 with the roughened surface 21 of the take-up roll I surround stud 25 with a torsion spring 39 having one end 40 thereof extending into the bearing 16 and having the other end 41 thereof extending into the hub 29 of lever 28. This spring tends normally to hold lever 28 to the left as viewed in Figs. 2 and 4 to maintain driving connections between rolls 15 and 32. Hub 29 is held by the spring against a collar 42 adjustably held to the inner end of stud 25 by means of a set screw 43. A clip 44 formed as indicated in Figs. 2 and 3 may be held to the breast beam by means of a screw 45 and extends around the sheath 38 to hold the latter to the breast beam.

The flexible shaft extends as indicated in Fig. 1 preferably through the magazine M and has its outer end attached to the front thread gear 19. One manner of attaching the flexible shaft to gear 19 is indicated in Fig. 5. The thread holder includes a support 50 having a bearing 51 in which rotates a short shaft 52 to the right end of which, see Fig. 5, the front thread engaging gear 19 is secured in a manner similar to that set forth in the aforesaid Payne patent. The left end of shaft 52 has a tapered thread 53 and is split as at 54. A nut 55 having a tapered thread fits around the tapered screw threads 53 and when tightened forces the split end of shaft 52 against the core 36 of the flexible shaft, the core extending into the shaft 52 for this purpose. The core 36 is thus secured at its two ends by similar means to the shafts 31 and 52.

A plate 60 secured to the support 50 has 75

mounted thereon a clamp 61 through which the sheath 38 of the flexible shaft extends. The clamp 61 has two upwardly extending arms 62 one of which is shown in Fig. 5. These arms are drawn together by any suitable means designated at 63 so that the sheath will be held tightly to the support 50 by the clamp 61. The latter has a flange 65 which may be secured in any approved manner to the plate 60. The structure shown in Fig. 5 may be similar to that shown in my co-pending application Serial No. 532,093, filed April 21, 1944.

In operation, the fabric F is moved forwardly by rotation of the take-up roll 15 and the latter causes turning of the small roll 32 in a clockwise direction as viewed in Fig. 2, thus turning the stub shaft 31 and core 36 of the flexible shaft in such a direction as to cause thread gear 19 to turn in the proper direction to tension the weft ends W. As shown in Figs. 2 and 3 the take-up roll 15 is approximately two and one-half times the diameter of the roll 32, but I am not limited to this relationship, inasmuch as a smaller roll can be employed if it is desired to turn the thread gears 19 and 20 at a faster rate.

After placing fresh bobbins in the magazine it is customary for the operator to turn the thread gears manually to tighten the new weft ends and draw them between the thread gears. If roll 32 were on a fixed axis it would be held against rotation by the take-up roll and prevent manual turning of gears 19 and 20. Under usual running conditions the spring 39 holds the surface of roll 32 against the take-up roll firmly enough to press the sand or other projections on roll 15 against and in close engagement with the small roll 32 to establish a frictional driving contact between the rolls. When gears 19 and 20 are turned manually at a rate faster than normal a rotary force is transmitted back through the flexible shaft 37 to roll 32 and the latter moves a slight distance away from the take-up roll and out of its previous close driving relation with roll 15. This slight movement is permitted by spring 39, but after the operator has completed turning of gears 19 and 20, the spring again restores normal driving relation between the rolls.

From the foregoing it will be seen that I have provided simple means by which the thread gears 19 and 20 of the thread holder may be driven from the roughened or friction surface of the cloth take-up roll of a loom. The train of driving connections between the take-up roll and the thread gears includes a small roll held against the surface 21 of the take-up roll and caused to rotate by the latter for the purpose of turning the core 36 of the flexible shaft. The latter in turn is connected to one of the meshing thread gears and it is in this manner that the slow but continuous rotation of the take-up roll 15 causes uniform turning of the thread holder gears during loom operation to take up slackness in the weft ends resulting either from replenishing operations or rotation of the bobbins. The spring 39 also yields to permit manual turning of gears 19 and 20 by the operator when new bobbins are placed in the magazine.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having reserve

bobbins from which weft ends extend, a cloth take-up roll having a friction surface rotating during loom operation, meshing geared members between which the weft ends extend and rotatable to tension the latter, rotary means engaging said friction surface and rotated thereby as said surface rotates, and driving connections between said rotary means and geared members causing the latter to rotate to tension said weft ends when the rotary means rotates.

2. In a weft replenishing loom having meshing thread gears rotatable to tension the weft ends of reserve bobbins, cloth take-up means rotating during loom operation and having a friction surface turning therewith, a roll engaging said friction surface and caused thereby to rotate as the take-up means rotates, and driving connections between said roll and said thread gears causing the latter to turn to tension said weft ends as the roll is rotated by said friction surface.

3. In a weft replenishing loom having meshing thread gears rotatable to tension the weft ends of reserve bobbins, cloth take-up means having a friction surface rotating therewith during loom operation, a roll having a friction surface of the take-up means, said friction surfaces cooperating to cause rotation of said roll as the take-up means rotates, and driving connections between said roll and gears to rotate the latter to tension said weft ends as the take-up means rotates.

4. In a weft replenishing loom having meshing thread gears rotatable to tension the weft ends of reserve bobbins, cloth take-up means having a friction surface rotating therewith during loom operation, a roll engaging and rotated by said friction surface as the take-up means rotates, and a flexible shaft connecting said roll to one of said thread gears to cause the latter to turn to tension said weft ends as said roll rotates.

5. In a weft replenishing loom having meshing thread gears rotatable to tension the weft ends of reserve bobbins, cloth take-up means rotating during loom operation and having a friction surface turning therewith, a lever pivoted with respect to the loom, a roll on said lever, means acting on said lever holding said roll against said friction surface to cause the latter to rotate said roll as the take-up means rotates, and driving connections between said roll and thread gears causing the latter to turn to tension said weft ends as the roll rotates.

6. In a weft replenishing loom having meshing thread gears rotatable to tension the weft ends of reserve bobbins, cloth take-up means having a friction surface rotating therewith during loom operation, a lever pivoted with respect to the loom, a roll on said lever, means acting on said lever holding the roll against said friction surface to cause the latter to rotate said roll as the take-up means rotates, and a flexible shaft connecting said roll to one of said thread gears to cause the latter to turn to tension said weft ends as said roll rotates.

7. In a weft replenishing loom having meshing thread gears rotatable to tension the weft ends of reserve bobbins, a cloth take-up cylinder having a friction surface rotating about the axis of said cylinder as the latter rotates during loom operation, a bearing for said take-up cylinder, a stud on said bearing parallel to the axis of said take-up cylinder, a lever pivoted on said stud, a roll rotatable on said lever, resilient means act-

ing on said lever to hold the roll against said friction surface and causing the latter to rotate said roll as the take-up cylinder rotates, and driving connections between said roll and gears causing the latter to turn to tension said weft ends as said roll rotates.

8. In a weft replenishing loom having meshing thread gears rotatable to tension the weft ends of reserve bobbins, a cloth take-up cylinder rotating during loom operation and having a friction surface turning therewith about the axis of the cylinder, a bearing for said take-up cylinder, a stud on said bearing parallel to the axis of said take-up cylinder, a lever pivoted on said stud, a roll rotatable on said lever, resilient means acting on said lever to hold the roll against said friction surface to cause the latter to turn said roll as the take-up cylinder rotates, and a flexible shaft connecting said roll to one of said thread gears to cause the latter to turn to tension said weft ends as said roll rotates.

9. In a weft replenishing loom having meshing thread gears rotatable to tension the weft ends of reserve bobbins, a cloth take-up cylinder having a friction surface rotating about the axis of the cylinder during loom operation, a bearing for said take-up cylinder, a stud on said bearing parallel to the axis of said take-up cylinder, a lever pivoted on said stud, a roll rotatable on said lever, a torsion spring surrounding said stud and connected to said bearing and lever and acting on the latter to hold the roll against said friction surface, thereby causing the latter to turn said roll as the take-up cylinder rotates, and driving connections between said roll and gears causing the latter to turn to tension said weft ends as said roll rotates.

10. In a weft replenishing loom having meshing thread gears rotatable to tension weft ends of reserve bobbins, cloth take-up means rotating during loom operation and having a friction surface turning therewith, a roll engaging said friction surface, yieldable means normally holding said roll in driving engagement with the friction surface to cause the latter to turn the roll as the take-up means rotates, and driving connection between said roll and gears normally turning the latter to tension said weft ends as the take-up means rotates, said means being caused to yield to permit said roll to move out of driving engagement with said friction surface by a rotary force transmitted through said driving connections and permit said roll to turn independently of said friction surface when the gears are turned manually.

11. In a weft replenishing loom having meshing thread gears rotatable to tension weft ends of reserve bobbins, cloth take-up means rotating during loom operation and having a friction surface turning therewith, a roll engaging said friction surface, yieldable means normally holding said roll in driving engagement with the friction surface to cause the latter to turn the roll as the take-up means rotates, a flexible shaft connecting said roll to one of said gears and normally turning the latter to tension said weft ends as the take-up means rotates, said means being caused to yield to permit said roll to move out of driving engagement with said friction surface by a rotary force transmitted through said flexible shaft and permit the roll to turn independently of said friction surface when the gears are turned manually.

WALTER H. WAKEFIELD.
